UNITED STATES PATENT OFFICE.

MEIJI NAKAMIZO, OF SAN FRANCISCO, CALIFORNIA.

CARRIAGE-TOP.

1,149,162.

Specification of Letters Patent.

Patented Aug. 3, 1915.

Application filed December 5, 1914. Serial No. 875,615.

To all whom it may concern:

Be it known that I, MEIJI NAKAMIZO, a citizen of the United States, residing in the city and county of San Francisco and State 5 of California, have invented new and useful Improvements in Carriage-Tops, of which the following is a specification.

This invention relates to a carriage top.

It is one of the objects of the invention 10 to provide a simple, substantial carriage top of the folding type such as is used on automobiles, and the like, and particularly to provide a construction which will permit a single person to raise or fold the top without 15 any assistance.

Further objects will hereinafter appear.

The invention consists of the parts and the construction and combination of parts as hereinafter more fully described and 20 claimed, having reference to the accompanying drawings, in which—

Figure 1 is a side elevation showing the top raised. Fig. 2 is a horizontal section on line 2—2 of Fig. 1. Fig. 3 is a detail side 25 elevation showing the top folded. Fig. 4 is a vertical transverse section on line 4—4 of Fig. 1. Fig. 5 is a vertical transverse section on line 5—5 of Fig. 1.

More particularly described, A indicates 30 the top edge of an automobile body. Secured on said edge by screws 2, or built right into the body, is a sectional channel shaped bar B; there being one bar on each side of the body.

Pivoted, as at 3, between the rear ends of the channel bars is the rear bow 4 of a folding top, generally indicated at C, and formed on each bar in alinement with said pivots is an extension bracket 5 which 40 is adapted to receive the front bow 6 when the top is folded back, as indicated in Fig. 3. The lower ends of the front bow are each provided with an outwardly extending bearing pin 7, and these pins are adapted to be 45 projected through the extension brackets 5 and secured therein by means of cotter pins 8.

The front end of each bar is perforated, 50 as at 9, and the pins 7, on the lower ends of the front bow, are similarly adapted to be projected through said perforations, as indicated in Fig. 1 and secured therein by cotter pins 8 when the top is raised. The channel bars are each provided with ingress 55 and egress openings 9' and 10 respectively,

and each channel is curved outwardly, as at 11, near the rear end and inwardly, as at 12, near the front end for purposes hereinafter to be described. Each channel is, furthermore, partly covered by a flange 13 30 to form a guide for the pins 7, or, in other words, to prevent the ends of the bow from jumping out of the channel bars while being moved from one end of the bar to the other.

The operation will be as follows: When it 35 is desired to raise the top, it is accomplished by first removing the cotter pins 8 from pins 7 on the lower ends of the front bow. The tendency of this bow is to spring outward and the ends will, therefore, when 40 released, have to be pushed a slight distance forward until pins 7 have entered the partly covered channel sections. The person raising the top may now walk to the rear of the machine and lift the top up, causing the 45 rear bow 4 to assume a vertical position, while the front bow will be caused to slide forward on the channel bars, as indicated by dotted lines at 15, Fig. 1. The front bow may now be pulled completely over to the 50 front end of the bars and will here spring out through openings 10, causing pins 7 to be 55 projected through the perforations 9 where they may be secured by the cotter pins 8. The front braces 16 may now be opened 60 and the guy straps (not here shown) attached to secure the top in its raised position.

The slight curve formed in the channel 65 at each end of the bar is provided for the following reason: After the front bow is released with relation to the rear supporting brackets 5 and the lower ends thereof have been inserted in the channel, everything is ready and the top may be raised. The raising 70 of the top causes the lower ends of the bow to slide forward in the channels, as indicated by dotted lines in Fig. 1. The curve indicated at 11 permits the tension in the bow to be partly released, thereby permitting 75 the bow to slide forward with the least friction possible. The curve indicated at 12 forces the lower ends of the bow inward again, increasing the tension to such an extent that when the ends finally enter openings 10 they will immediately spring out, causing pins 7 to enter perforations 9 without 80 any outside assistance.

The bars are made in sections 32, 33 and 85 34 to permit the door 35 to be opened at any 90

time. The bars constructed as here shown are simple and substantial in construction and may be easily attached or built in any machine. Any number of movable bows 5 may be used in connection with the bars and practically any form of top construction may be employed. The important feature is that the provision of the bars makes it possible for one person to raise or close the 10 top without any outside assistance.

The materials and finish of the carriage top are such as the experience and judgment of the manufacturer may dictate.

I wish it understood that various changes 15 in form, proportions and minor details of construction may be resorted to within the scope of the appended claim and that I do not wish to limit myself to the specific design and construction here shown.

20 Having thus described my invention, what

Copies of this patent may be obtained for five cents each, by addressing the "Commissioner of Patents, Washington, D. C."

I claim and desire to secure by Letters Patent is—

The combination with the bows of a foldable automobile top and the body of the automobile, of channel bars secured in the 25 top edge of the body, one on each side, means for pivotally connecting all of the top supporting bows to the rear end of said bars, and a pivotal connection formed at the front end of each bar adapted to receive and support the front movable bow of the top, said bars being curved at each end, substantially as and for the purpose described.

In testimony whereof I have hereunto set my hand in the presence of two subscribing 35 witnesses.

MEIJI NAKAMIZO.

Witnesses:

JOHN H. HERRING,
W. W. HEALEY.
